GAME

De Witt V. B. Thomas, East Orange, N. J.

Application March 19, 1935, Serial No. 11,752

2 Claims. (Cl. 273—141)

This invention relates to game apparatus; and the invention has for its principal object to provide a game board having a novel "play" indicating means subject to actuation by the player, said 5 indicating means comprising a pivoted spinner and means cooperative therewith whereby, as the spinner comes to rest after actuation, the same is caused to positively and indubitably register with but one of a plurality of "play" instructions with 10 which the game is provided, and which are disposed in surrounding relation to the indicating means.

This invention has for a further object to provide in combination with a game board, having 15 indicating means as above characterized, interchangeable or detachable game sheets or cards for various games subject to selective application to and use with the game board and its "play" indicating means.

Other objects of this invention, not at this time more particularly enumerated, will become apparent in the following detailed description of the same.

An illustrative embodiment of this invention is shown in the accompanying drawing, in which:

Fig. 1 is a plan view of the novel game board having a game sheet or card applied thereon ready for play; Fig. 2 is a transverse sectional view, taken on line 2—2 in Fig. 1; and Fig. 3 30 is an enlarged fragmentary sectional view showing the details of the "play" indicating spinner and the stop means cooperative therewith.

Similar characters of reference are employed in the hereinabove described views, to indicate 35 corresponding parts.

Referring to the drawing, the reference character 5 indicates a main body or board, which may be of any suitable material, such, for example, as wood, card or paper board, metal, fibre, molded 40 condensation product or other molded material, etc.

Affixed to the main body or board 5, in upstanding relation to its upper face, and in any selected suitable location within the area thereof, is a 45 pivot post 6 upon which a metallic spinner 7 is mounted so as to freely revolve about the same when put in motion. Cooperative with said spinner 7 is a spinner stop means, preferably comprising a plurality of upstanding metallic projections 8, suitably affixed to the board 5, said projections 50 8 being spaced apart one from another and arranged to form a circular row concentrically surrounding said pivot post 6, and contiguous to the path of movement of said spinner when the latter is revolved upon and about said pivot post.

Either the spinner 7 or said projections 8 are magnetized or made of magnetic material, whereby a mutual magnetic attraction is exerted between the spinner and the given projection to which the active spinner extremity is opposed when coming to rest upon completing the revolving movement imparted thereto. By reason of the attractive magnetic force thus exerted, the spinner, upon completion of its revolving movement, is attracted to and brought into positive 10 aligned registry with some one of the projections 8 and is held stationary relative thereto, free from wavering or displacement by vibration, thus assuring a positive indication or pointing to the particular "play" instruction which may be correlated with that particular projection 8 and no other. It will be obvious therefore that the novel "play" indicating means, according to this invention, is positively determinative of the "plays" 15 governing the performance of the game, as will 20 presently more fully appear. It will be equally obvious that the novel "play" indicating means by preventing indeterminate indication, such as would occur were the spinner to come to rest between two "play" instructions and thus fail to 25 definitely indicate which "play" is permissible, thereby eliminates necessity for more or less frequent respinning of the spinner, with consequent loss of time and interruption of the interest of the game.

The specific forms of the pivot post 6, spinner 7 and projections 8 are all subject to more or less wide variation in structure. The accompanying drawing shows, by way of illustration, one very satisfactory construction and arrangement there- 35 of, wherein the pivot post 6 is provided with an enlarged supporting base 9 to rest on the top surface of the board 5, and with a riveting shank 10 of reduced diameter projecting downwardly 40 from its underside for passage through the body 45 of the board 5, so that its extremity may be riveted over, as at 11, to thus firmly affix the pivot post to the board. At its upper extremity, the pivot post 6 is provided with a needle point or conical pivot 12. The spinner 7, as shown, comprises an elongated metallic bar, preferably 50 shaped in simulation of an arrow, having a pointer end 13 of arrow-head shape and an opposite or tail end 14 of suitable design, preferably in simulation of the feathered tail of an arrow. Affixed to said spinner bar 7 intermediate its extremities is a bearing hub 15, having a neck 16 of 55 reduced diameter extending through the bar body, and riveted over the underside of the latter, as at 17, to thus affix said bearing hub there-

to. Formed in and extending upwardly from the lower end of said bearing hub 15 is an axial chamber 18, terminating at its upper end in a conical bearing seat 19. When the spinner 1 is operatively assembled with and upon the pivot post 6, the latter extends upwardly through the bearing hub chamber 18 of the former, so that the conical bearing seat 19 seats itself upon the conical pivot 12 of the post 6. In this manner the spinner 1 is supported upon the post 6 so as to be capable of free and easy rotation, with a minimum of friction. The upwardly projecting bearing hub 15 of the spinner 1 likewise serves as a finger-piece, which may be twisted by the player's fingers to impart the desired rotative movement to the spinner. In order to prevent accidental displacement of the spinner from the pivot post, and consequent risk of loss thereof, the post is provided with an annular groove or channel 20 below its conical pivot 12, and threaded through the wall of said spinner bearing hub 15 is a keeper screw 21 having a reduced terminal portion 22 at its inner extremity to engage in said groove or channel 20 of the post. It will be obvious that this arrangement will prevent withdrawal of the bearing hub 15 from the post 6 without, however, in any way impeding the rotation of the hub relative to the post. The projections 8 may constitute individual elements separately attached to the board 5, but preferably, the same may be more conveniently produced and assembled with and fastened to the board 5 when made as integral elements of a base ring. For example, as shown in the drawing a base ring 23 is provided, the same having an upward extension from one circumferential periphery thereof an up-turned flange having a plurality of equi-spaced vertical slits or open spaces 24 to thereby divide the same so as to form the desired plurality of upstanding circumferentially spaced apart tongues or projections 8, the free end portions of which lie concentric and contiguous to the path of movement described by the pointer end 13 of the spinner 1. The base ring 23 is imposed upon the top face 45 of the board 5 so as to be concentric to the pivot post 6, and is secured in such position by any suitable fastening means, such e. g. as rivets 25.

A game board of suitable design over or upon which playing pieces are movable according to 50 "play" instructions indicated by the resting position of the spinner 1, may be permanently applied to the upper face of the board 5. In the preferred form of the invention, and to fulfill one of the objects thereof, separable game cards or 55 sheets 26 are provided, the same having an opening 27 to engage over the indicating means of the board 5, and having a plurality of "play" instruction panels or indicia 28 corresponding to the projections 8, and adapted to lie exteriorly 60 contiguous thereto and in registry therewith. If desired the board 5 may be further provided with an upstanding keeper-peg 29, and the sheet or card 26 with a corresponding perforation 30 engageable therewith, so as to prevent accidental 65 shifting of the sheet or card as applied to the board for use. Of course, any other means to secure the card or sheet 26 to the board against accidental displacement or shifting may be employed. A plurality of game sheets 26, designed 70 for a variety to different types or kinds of games, may be provided for interchangeable use on the board 5. Illustrative of the general character

of game card or sheet, that shown in the accompanying drawing is designed to provide an air race game, and comprises a geographical map having different around the world air routes depicted thereon with indicated stopping points at 5 various places. The instruction indicia 28 of such game indicate various "hop" distances and the movement of the pieces 31, representing the airship of the players, is governed by following the instructions indicated for each play, as the players in turn revolve the spinner 1 and the latter comes to rest in various "play" indicating positions. If desired, the game sheets or cards may be perforated to provide openings 32 corresponding to various "play" positions to which the pieces 15 31 may be moved, and the underlying board 5, in such case, may be correspondingly perforated to provide openings 33 to match the perforations of the various game sheets or cards to be used therewith. Such arrangement permits the use 20 of playing pieces 31 having positioning pins 34 enterable in the openings 32-33 to secure the said pieces against accidental displacement from the positions to which they are from time to time moved during the course of the game. 25

In practice it has been found to be preferable to magnetize the spinner bar 1, the extremities of which thereby provide portions of definite or fixed polarity, in which case the projections 8 may be made of unmagnetized iron or steel. 30

Since many changes, in addition to those already indicated, may be made in the hereinabove described constructions, and different embodiments of this invention could be made without departing from the scope thereof as defined in 35 the following claims, it is intended that all matter contained in the above description or shown in the accompanying drawing shall be interpreted as illustrative and not in a limiting sense. 40

I claim:—

1. A "play" indicating device for games, comprising a board, a pivot post upstandingly mounted on said board, a spinner bar of magnetized metal having a hollow bearing hub intermediate its ends to rotatively engage over said pivot post for balancing said spinner bar upon the latter for revolution about the axis thereof, a metallic base ring affixed to said board concentric to said pivot post, said base ring having an annular row of fixed upstanding metallic projections 50 spaced apart by intervening air gaps in concentric relation to the axis of said pivot post and adjacent to the path of revolving movement of said spinner bar extremities. 45

2. A "play" indicating device for games, comprising a board, a pivot post upstandingly mounted on said board, a spinner bar of magnetized metal having a hollow bearing hub intermediate its ends to rotatively engage over said pivot post for balancing said spinner bar upon the latter for revolution about the axis thereof, a metallic base ring affixed to said board concentric to said pivot post, said base ring having an annular row of fixed upstanding metallic projections 60 springing from its outer periphery, said projections being spaced apart by intervening air gaps in concentric relation to the axis of said pivot post and adjacent to the path of revolving movement of said spinner bar extremities, and means to prevent accidental displacement of said spinner bar bearing hub from said pivot post. 65
